US0D1090651S

(12) **United States Design Patent** (10) **Patent No.:** **US D1,090,651 S**
(45) **Date of Patent:** **** Aug. 26, 2025**

(54) **WORKSTATION**

(71) Applicant: **INTELLIGRATED HEADQUARTERS, LLC**, Mason, OH (US)

(72) Inventors: **Mark Lee Oberpriller**, Atlanta, GA (US); **Anthony James Turco**, Liberty Township, OH (US); **Jarl Nicholas Sebastian**, Trenton, OH (US); **Michael James Wells**, Lake Stevens, WA (US); **Richard Graff**, Cincinnati, OH (US)

(73) Assignee: **INTELLIGRATED HEADQUARTERS, LLC**, Mason, OH (US)

(**) Term: **15 Years**

(21) Appl. No.: **29/878,697**

(22) Filed: **Jun. 26, 2023**

Related U.S. Application Data

(63) Continuation of application No. 29/773,612, filed on Mar. 10, 2021, now Pat. No. Des. 993,998.

(57) **CLAIM**

The ornamental design for a workstation as shown and described.

DESCRIPTION

FIG. 1 is a front perspective view of a workstation showing the new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines depict portions of the workstation that form no part of the claimed design.

1 Claim, 7 Drawing Sheets
